Matthew Burton
By Chas. Tillman, Atty.

UNITED STATES PATENT OFFICE.

MATTHEW BURTON, OF BATAVIA, ILLINOIS.

MECHANICAL MOVEMENT.

SPECIFICATION forming part of Letters Patent No. 738,770, dated September 15, 1903.

Application filed February 11, 1903. Serial No. 142,920. (No model.)

To all whom it may concern:

Be it known that I, MATTHEW BURTON, a citizen of the United States, residing at Batavia, in the county of Kane and State of Illinois, have invented certain new and useful Improvements in Mechanical Movements, of which the following is a specification.

The object of this invention is to provide a simple and inexpensive device for rotating a shaft, preferably an agitator-shaft of a washing-machine or churn, alternately in opposite directions by a continuous rotary movement of a driving-shaft; and it consists in certain peculiarities of the construction, novel arrangement, and operation of the various parts thereof, as will be hereinafter more fully set forth and specifically claimed.

The improvement is susceptible of various changes in the form, proportion, and minor details of construction without departing from the principle or sacrificing any of the advantages thereof, and a full disclosure of the invention and adaptation of the same is shown in the accompanying drawings, in which—

25 Figure 1 is a view in side elevation and partly in section of a movement embodying my invention, showing it mounted on a portion of the top of a washing-machine or churn; and Fig. 2 is a plan view taken on line 2 2 of Fig. 1 looking in the direction indicated by the arrows.

Like numerals of reference refer to corresponding parts throughout the different views of the drawings.

35 The reference-numeral 5 represents in the present instance a portion of the tub of a washing-machine, but it may represent a portion of a churn or other vessel in which it is desired to agitate or stir the contents thereof.

40 Mounted on the top or lid 6 of the vessel is the supporting-frame 7 of my movement, which frame may be made of any suitable size, form, and material, but preferably of the shape shown in the drawings. Vertically journaled in upper and lower extensions 8 and 9, respectively, of the supporting-frame is a rotary reciprocal or agitator shaft 10, which passes through the cover or lid 6 of the tub or other vessel and has suitably mounted on

45 its lower portion an agitator or dasher 11 of any desired construction. The shaft 10 is provided with a worm 12 to engage a worm-

groove 13 on the inner surface of the sleeve 14, which is movably mounted on said shaft. This sleeve is furnished with a vertical rack-bar 15 and has on each side of said rack-bar a guide-flange 16, which serves to hold the rack-bar in engagement with the beveled pinion 17, which is mounted on the inner portion of the driving-shaft 18, which shaft is journaled on the supporting-frame 7 and carries on its outer portion a crank-wheel 19, used for turning the same.

55 By rotating the driving-shaft 18 continuously in one direction it is apparent that the pinion 17 thereon will engage the teeth of the rack-bar first on one of its surfaces until it reaches the end thereof, when the pinion will pass over the end of the rack and engage the other side of the teeth thereof, thus causing the sleeve 14 to move longitudinally on the worm portion of the shaft 10, so as to impart thereto a rotary reciprocal or alternating rotary movement, in which operation the flanges 16, which are located far enough from the 75 rack-bar to receive the inner end of the driving-shaft, will hold the rack-bar in positive engagement with the pinion.

Having thus fully described my invention, what I claim as new, and desire to secure by Letters Patent, is—

1. In a mechanical movement, the combination with a rotary reciprocal shaft, of a sleeve movably mounted thereon and in worm-thread engagement therewith, a rack located longitudinally on said sleeve, a continuously-revolvable shaft, and a pinion thereon to engage the rack, substantially as described.

2. In a mechanical movement, the combination with a rotary reciprocal shaft, of a sleeve movably mounted thereon and in worm-thread engagement therewith, a rack located longitudinally on said sleeve, a guide-flange located on the sleeve near each side of the rack, a continuously-revolvable shaft having its inner end projected so as to extend between said flanges and rack, and a pinion on said shaft to engage the rack, substantially as described.

3. In a mechanical movement, the combination with a rotary reciprocal shaft provided with a worm, of a sleeve movably mounted on said shaft and having a groove to receive the worm thereof, a rack located longitudi-

nally on said sleeve, a continuously-revoluble shaft, and a pinion thereon to engage the rack, substantially as described.

4. In a mechanical movement, the combination with a rotary reciprocal shaft provided with a worm, of a sleeve movably mounted on said shaft and having a groove to receive the worm thereon, a rack located longitudinally on said sleeve, a guide-flange located on the

sleeve near each side of the rack, a continuous revoluble shaft having its inner end projected so as to extend between said flanges and rack, and a pinion on said shaft to engage the rack, substantially as described.

MATTHEW BURTON.
